UNITED STATES PATENT OFFICE.

GEORGE P. GANSTER, OF READING, PENNSYLVANIA.

CLOCK-WORK ESCAPEMENT.

SPECIFICATION forming part of Letters Patent No. 269,278, dated December 19, 1882.

Application filed April 10, 1882. (No model.)

To all whom it may concern:

Be it known that I, GEORGE PETER GANSTER, of Reading, in the county of Berks and State of Pennsylvania, temporarily residing 5 in Newark, in the county of Essex and State of New Jersey, have invented certain new and useful Improvements in Escapements, of which the following is a specification.

This invention is intended for application to 10 clocks, watches, chronometers, and other time-keeping machinery, or to music-boxes and other machinery in which an approximately exact rate of revolution is important. I have in my experiments applied it to a small style of 15 clock. The nature of the escapement allows the machinery to be worked in any position indefinitely.

My device has the peculiarity that it does 20 not offer in any part of its motion a dead-point, and consequently does not require a special act of starting it, as is the case in ordinary escapements. All that is required is to apply 25 the power to the mechanism to be regulated, either by winding a spring or applying a weight, or in any other suitable manner.

The accompanying drawings form a part of 30 this specification, and represent what I consider the best means of carrying out the invention.

Similar letters of reference indicate corresponding parts in all the figures.

Figure 1 is a front elevation of my new device. Fig. 2 is a rear elevation of a part thereof, a part of the framing being broken away 35 to more clearly show certain details. Fig. 3 is a plan of Fig. 2. Fig. 4 is a front elevation of a similar device, showing a different mode of regulating or adjusting the escapement. Fig. 5 is a front elevation of a modification. 40 Fig. 6 is a side elevation of Fig. 5.

A is the escapement-wheel, supported in suitable bearings and receiving motion through a pinion, a, on its shaft from a wheel, X, (shown in dotted lines in Fig. 1,) the latter 45 wheel forming part of the train of mechanism which the device is intended to regulate. The escapement-wheel A is formed on its periphery with notches 1, 2, 3, 4, &c. Shafts b c turn in suitable bearings on opposite sides of 50 the escapement-wheel.

B C are wheels mounted on b c. Each is formed with a segment of teeth, B' C', which engage with each other, compelling the wheels

B C to turn in harmony in opposite directions. In each of the disks B C, near its shaft, 55 is set a pin, b' c', respectively, in such position that it can engage with and be acted upon by the notched surface of the escapement-wheel A. The wheels B C are of considerable weight, or have weights B² C² affixed to them, 60 which should be balanced so that the centers of gravity shall coincide with the axes of the respective shafts b c. In order to attain this, screws b² c², with heavy heads, may be inserted radially in those weights, as indicated in Fig. 65 1. By turning these screws in the proper direction the center of gyration of each disk may be shifted outward or inward, always taking care that the center of gravity of each coincides with the axis of its shaft. The bear- 70 ings of the shafts b c are carried on brackets B³ C³, which are capable of swiveling on center screws, B⁴ C⁴, and may be adjustably held in the proper position by means which will be described farther on.

The operation of the parts so far as described 75 is as follows: Supposing the parts to be in the position illustrated in Fig. 2, the escapement-wheel A having a tendency to turn in the direction of the heavy arrow x, the pin c' being 80 engaged in the notch 1, and the pin b' having just left the notch 9, and being on the point between the notches 9 and 8 of the escapement-wheel, on the further turning of the latter the lower edge of notch 1 will strike against the 85 pin c', causing the wheel C to commence a rotary motion in the direction of the arrow y, but the disks B and C being geared together the disk B will be compelled to turn in the direction of the arrow z. Thus the pin b' will 90 move into the notch 8 without effectively touching it, while pin c' will come to the point between notches 1 and 15. At that moment, in consequence of the further revolution of escapement-wheel A, pin b' is struck by the upper 95 edge of notch 8, whereby the motion of disk B will be reversed, compelling also disk C to turn in the opposite direction. This brings pin c' into notch 15 and pin b' on the point between notches 8 and 7. It will thus be seen that by 100 the power applied to escapement-wheel A a succession of oscillations or partial rotations in alternately opposite directions is imparted to the wheels B and C, and as the latter are heavy, or carry considerable weight, involving 105 an inertia which is to be overcome at each re-

versing of their rotation by the contact of one or the other of the pins $b' c'$ with the escapement-wheel A, the motion of the latter is retarded to just the sufficient extent. Setting 5 the wheels B C nearer together makes the clock or other machine controlled by the escapement go slower; setting these wheels farther apart makes it go faster. If the wheels are set apart so that the pins $b' c'$ enter quite to the bottom 10 of each notch 1, 2, &c., the motion of the escapement-wheel will be very slow, because it will have to give a large throw in either direction to the disks or balance-wheels B C. If, on the contrary, the pins $b' c'$ hardly enter the 15 notches of the escapement-wheel, the motion will be much quicker, as the escapement-wheel turns freely a greater part of a revolution until the edges of its notches operate against the pins. It follows, therefore, that a simple method 20 of regulating or rectifying consists in simply moving the shafts $b c$, and consequently the wheels B C, slightly away from or toward each other, and consequently away from or toward the center of the escapement-wheel. For this 25 purpose the brackets $B^3 C^3$, carrying the disks or balance-wheels B C, are mounted with capability to swivel, as has been above described, and are provided with means for varying their position with reference to the escapement-wheel 30 A. This may be accomplished by the device illustrated in Fig. 1, where their downward-projecting ends are traversed each by a screw, E, the heads of said screws E being held against end motion in grooves formed for the purpose 35 in the fixed framing, so that by turning these screws E in one direction or the other the brackets are caused to slightly oscillate and bring their upper ends, carrying the disks, toward or away from the escapement-wheel A. It will be 40 noticed that this mode of regulating allows each of the brackets to be adjusted separately, which for fine work may offer considerable advantages, as it allows the pins $b' c'$ to be set both exactly in a same position with reference 45 to the notches of the escapement-wheel, even if there should be a slight error in the construction of the device.

Where exact time-keeping is important the winding should be done at regular periods, 50 winding always to a definite stop, as is common in time-keepers. During the first part of the period intervening between one winding and the next the machine will run with a velocity somewhat above the average. During 55 the last part it will run with a velocity below, but the mean velocity will be very uniform so long as the same mainspring and the same adjustment thereof and the same weight and diameter of the oscillating wheels are preserved.

The invention possesses marked advantages over any ordinary escapement for all machines where considerable power is involved.

Fig. 4 shows the construction of adjusting 65 means which I employ under many ordinary circumstances. The adjustment is effected by one operation simultaneously for both disks B

C. From the lower extremity of each bracket $B^3 C^3$ projects a pin, $b^3 c^3$, respectively, which pins are engaged in eccentric slots e , formed in 70 a plate, E, which swivels on a center, e' , and from which may project an index-hand, E', showing on a scale the exact relative positions of the parts. When the index is turned, for instance, to the right in Fig. 4, the slots e , 75 through the pins $b^3 c^3$, cause the lower extremities of the brackets to move apart, and thus bring the disks B C in somewhat closer proximity to the center of the shaft a' , which, as described above, has the effect of retarding 80 the motion of the escapement. If the index E' is turned in the opposite direction, the reverse effect is produced, as will be readily seen.

In the form of device shown in Figs. 5 and 85 6 the two oscillating wheels B and C are not geared together, but geared to an intermediate wheel, G. These three wheels B, C, and G may themselves be made of sufficient weight to involve sufficient inertia; but I propose to 90 extend the shaft of the intermediate wheel, G, and mount thereon a larger wheel, H. Instead of this, the shafts b and c may be extended, and may each carry large wheels. In this modification, as in the other, adjusting 95 the shafts $b c$ nearer together increases the range of the oscillations and makes the machinery go slower. The adjustment is effected by a screw, E, engaging in threaded segments formed on the lower ends of the brackets B^3 100 C^3 , as clearly indicated in Fig. 5.

Other modifications may be made in the forms and proportions of the details. I can make the wheels B C of compound construction, so that when subjected to changes of 105 temperature the expansion and contraction shall be equalized; but I do not esteem such generally necessary. The necessity for equalizing in ordinary time-keepers is largely due to the fact that they work by pendulums or hair-springs, which vary with changes of temperature. My escapement, by dispensing with those elements, avoids the errors incident thereto.

I claim as my invention—

1. An escapement having a notched escapement-wheel, as A, and two balanced members, as B C, geared together and carrying studs $b' c'$, combined and arranged substantially as herein specified.

2. In an escapement, the notched escapement-wheel A and members B C, having pins $b c$, in combination with the adjustable brackets $B^3 C^3$, carrying the members B C, and with means, as E, for varying the distance between the centers of the members B and C, substantially as and for the purpose herein specified.

In testimony whereof I have hereunto set my hand, at New York city, New York, this 31st day of March, 1882, in the presence of two 130 subscribing witnesses.
